UNITED STATES PATENT OFFICE.

EDWARD SCHNELL, OF BARTLESVILLE, OKLAHOMA.

PUMPING VALVE FOR OIL WELLS.

1,405,447.

Specification of Letters Patent.

Patented Feb. 7, 1922.

Application filed March 29, 1921. Serial No. 456,683.

To all whom it may concern:

Be it known that I, EDWARD SCHNELL, a citizen of the United States, residing at Bartlesville, in the county of Washington and State of Oklahoma, have invented new and useful Improvements in Pumping Valves for Oil Wells, of which the following is a specification.

My invention relates, in general terms, to improvements in reciprocating pumps for oil and other artesian wells, and more particularly it is designed to provide means whereby accumulation of sand above the plunger of a pump will be trapped so that the cups 15 of the plunger will not be cut away and destroyed.

It has been found that in pumping oil from wells considerable sand accumulates above the plunger and soon cuts away the cups 20 thereof, and this is especially true where the well has been sunk to a considerable depth, for after the oil has been pumped off a column of liquid remains standing in the tubing of approximately the same depth as 25 the well, and while much of the sand held in suspension by the oil is carried off with the oil, the sand in this remaining column of oil settles to the working valve. In order to prevent accumulation of sand about the 30 cups of a working valve during the operation of pumping, and also after the oil has been pumped off, there is provided above my improved plunger a novel sand trap which 35 intercepts the sand before it reaches the cups of the valve and thereby prevents them from being cut away and destroyed.

It is also one of the primary purposes of my invention to provide in conjunction with a pumping valve, a device for trapping sand 40 and other material of a granular nature whereby to remove the same from the working barrel and tubing of a well when the sucker rods and valve are withdrawn thus scavenging the tubing at the same time the 45 sucker rod is pulled.

Furthermore, it is also an object of my invention to provide an improved pumping valve or plunger the parts of which can be quickly assembled and disconnected for re- 50 placement and cleaning.

To these and other ends, my invention consists in the construction, arrangement and combination of parts described hereinafter and pointed out in the claims forming a part 55 of this specification.

One embodiment of my invention is repre-

sented by way of example in the accompanying drawings, wherein:—

Figure 1, is a side elevation of my pumping valve and trap assembled, for disposition 60 in the working barrel of a well (not shown).

Figure 2, is a sectional side view of my valve showing the arrangement of its separate parts.

Figure 3, is a view taken on the line 3—3 65 of Figure 2, and

Figure 4, is a view taken on the line 4—4 of Figure 2.

Like characters of reference refer to like or similar parts throughout the several views 70 of the drawings, in which:—

The body of my valve is formed of a reduced section of pipe (2) the upper and lower ends of which are screw-threaded for the reception, respectively, of a nut (3) and 75 a cylindrical extension (4). The nut (3) is internally screw-threaded from one of its ends for the reception of the pipe section (2) and externally screw-threaded from its other end for the reception of a three-way 80 ball valve casing (5), carrying the usual ball (6), and provided with a screw-threaded reduced projection (7) upon which the ends of the sucker rods of the pump (not shown) are engaged. The cylindrical extension (4) 85 has an annular flange (8) formed upon its pipe-engaging end and is provided with screw threads and opposed slots (9) in its opposite end for the reception of a locking nut (10). The nut (10) has openings (11) 90 formed therein for the reception of a split pin (12) engaging within the slots (9) to lock the same in place. The cylindrical extension (4) is further provided intermediate its ends with screw threads (13) upon which 95 is engaged a nut (14) seated against the lower end of which is the uppermost of a plurality of suction cups (15).

The annular rings (16) for supporting and spacing the cups (15) are of increased 100 thickness from one of their edges to their other edge so that when they are placed in position (see Figure 1) the broad edge will form a supporting seat for the cups (15), which, it will be understood, are retained in 105 place by the alternate interposition of the retaining rings. The lowermost retaining ring is held in place by the locking nut (10) and as the nut (10) is adjustable within certain limits the pressure exerted thereby upon the 110 suction cup assembly can be increased or decreased at will.

5   Mounted above the nut (15) and enveloping approximately the entire length of the pipe (2) but spaced therefrom, is a cylinder (17) one end of which is formed with an internal annular flange (18) which engages the flange (8) upon the cylindrical extension, and is held rigidly thereagainst by the nut (15). This cylinder (17) forms a sand trap for preventing accumulation of sand 10 about the cups (15), and in diameter it should be slightly less than the diameter of the working barrel of the well within which the entire tool is adapted to be disposed.

15   In assembling my pumping valve or plunger the ball valve casing (5) is engaged with the nut (3) and the nut (3) is screwed upon the upper end of the pipe section (2), whereupon the cylindrical extension (4) is screwed upon the opposite end of the pipe (2) and 20 the trapping cylinder (17) moved into place with its flange (18) engaging the flange (8) upon the cylindrical extension (4). In order to hold the cylinder rigidly in place, the nut (14) (which may be, and preferably is, a lock nut) is screwed into place upon the threads (13), and the first of the cups (15) is moved into place, after which the rings (16) and the remaining cups are alternately assembled on the extension. The suction cup 25 assembly having been completed the locking nut (10) is mounted upon the extension (4) and screwed up to bring the proper pressure to bear against the suction cup assembly, whereupon the split pin (12) is inserted 30 through the nut (10) and slots (9) to complete the pumping valve or plunger assembly.

35   In operation, the oil follows a course defined by the cylindrical extension (4), pipe (2) and the valve, but as the sand through settling action returns again to the valve it is trapped between the pipe (2) and cylinder (17), and remains so entrapped until the valve or plunger is removed in its entirety from the well. It will consequently be seen that all sand is removed from the working barrel of the well (not shown) and from the tubing when the sucker rod and valve are removed and consequently new suction 40 cups may be replaced at any time and they will not be quickly cut away by sand already accumulated in the working barrel. Furthermore, the nature of the valve, and the peculiar arrangement of its parts enables an operator to quickly assemble it or take it down and replace any worn or broken parts.

45   While in the foregoing, there has been illustrated and described such combination and arrangement of elements as constitute 50 the preferred embodiment of my invention, it is nevertheless desired to emphasize the fact that interpretation of the invention should only be conclusive when made in the light of the subjoined claims.

55   Having described my invention and its ob-

jects with such attention to detail as will thoroughly acquaint one skilled in the art with its construction and advantages, I claim:

1. A pumping attachment for oil wells 70 comprising a hollow body portion, a flanged cylindrical extension separably attached to the body portion, and a cylindrical casing 75 separably mounted upon the extension and fixed rigidly against the flange thereof and extending about and spaced from the body portion for trapping sand and other material.

2. A pumping attachment for oil wells 80 comprising a hollow body portion, a cylindrical extension separably attached to the body portion, an annular flange on the extension, a cylindrical casing mounted on the extension and extending about and spaced from the body portion, an annular flange 85 formed on the casing, and the annular flange on the casing disposed to engage the annular flange on the extension whereby to rigidly mount the casing upon the extension.

3. In a pumping attachment for oil wells 90 including a body portion carrying a valve, and a flanged extension carrying suction cups, a cylindrical casing separably mounted upon the extension and enveloping and spaced from the body portion, and an internal annular flange formed on one end of the casing for engagement with the flange on the extension whereby to rigidly support the casing in spaced relationship to the body portion. 100

4. A pumping attachment for oil wells 105 comprising a hollow extension, an annular flange formed on the extension, a cylindrical casing provided with an internal annular flange receivable upon the extension and disposed with its flange engaging the annular flange on the extension, a hollow portion 110 separably connected with the extension and extending through the casing, a plurality of suction cups carried by the extension, means arranged on the extension between the suction cups and the casing and rigidly engaging the flange on the casing for holding the same in position, and an adjustable locking nut disposed upon the free end of the extension for preventing displacement of the suction cups. 115

5. A pumping attachment for oil wells 120 comprising a body portion, an extension separably engaged with the body portion, a flange on the extension, a nut on the extension, adjacent the flange, and a cylindrical casing mounted upon the extension and engaged adjacent one of its ends between the nut and the flange and locked against the flange by the nut whereby to trap sand and other material. 125

6. A pumping attachment for oil wells 130 comprising a body portion and an extension separably connected together, a flange on the

extension, a nut on the extension adjacent to the flange, a second nut on the extension removed from the flange and upon the end of the extension, suction cups carried upon the extension between the above mentioned nuts, and a cylindrical casing provided with a flange mounted upon the extension with its flange engaged with the flange of the extension and locked in position by the nut adjacent the flange of the extension. 10
5 In testimony whereof, I affix my signature hereto.

EDWARD SCHNELL.
